UNITED STATES PATENT OFFICE.

JAMES BATE, OF DETROIT, MICHIGAN.

DIE-CASTING MACHINE.

1,121,455.

Specification of Letters Patent. Patented Dec. 15, 1914.

Application filed December 27, 1913. Serial No. 809,007.

To all whom it may concern:

Be it known that I, JAMES BATE, a citizen of the United States, residing at Detroit, in the county of Wayne and State of Michigan, 5 have invented new and useful Improvements in Die-Casting Machines, of which the following is a specification.

This invention relates to a die casting machine, particularly of that type in which the 10 molten metal is ejected from the metal pot through an outlet or mouth piece by an expelling plunger, operated manually or by pneumatic means.

One object of the invention is to provide 15 a die casting machine having an outlet spout and mouth piece, together with a controlling valve of novel construction, whereby the metal may be discharged to cast either in a horizontal position in front of the 20 mouth piece or in a vertical position beneath the mouth piece.

A further object of the invention is to provide means whereby the plunger and 25 valve may be simultaneously operated to discharge or cut off the flow of the molten metal.

A further object of the invention is to provide a mouth piece or discharge nozzle having front and bottom discharge outlets 30 and attachments whereby the machine may be quickly and conveniently adapted for making castings of the character described, and also to provide an attachment whereby the machine may be adapted for making 35 vertical over-head castings, the machine being thus rendered of universal use in making the various kinds of castings in demand.

A still further object of the invention is to provide a mouth piece and attachments of the character set forth whereby the machine may be converted to make any 40 of the aforesaid kinds of castings in a ready, quick and convenient manner.

The invention consists of the features of 45 construction, combination and arrangement of parts herein fully described and claimed, reference being had to the accompanying drawings in which:

Figure 1 is a vertical section through a 50 die casting machine embodying my invention, showing the outlets and valve in closed position. Fig. 2 is a front elevation of the

same. Fig. 3 is an enlarged sectional view through the mouth piece showing the valve and front cut off plate in position for the 55 operation of the machine in making a front horizontal casting. Fig. 4 is a similar view showing the parts in position for making a vertical underhead casting. Fig. 5 is a detail section on the line 5—5 of Fig. 3. Fig. 60 6 is a bottom plan view of the controlling valve in the mouth piece. Fig. 7 is an enlarged detail view of the front gate or cut off plate. Figs. 8 and 9 are enlarged detail vertical sections of the cut off plug and valve 65 controlling the bottom outlet. Fig. 10 is a vertical section showing the use of the transfer tube or fitting for making overhead vertical castings. Fig. 11 is a detail view of the transfer tube or fitting detached. 70 Fig. 12 is a plan view of the plug or closure of the bottom outlet controlling the device.

Referring to the drawings, 1 designates the body or casing of the casting machine, 75 which supports a melting pot 2 heated by a suitable burner 3. The metal is discharged from the pot through a spout or conductor 4 which extends at its receiving end into the pot and is provided with a port 5 for the 80 flow of the metal thereinto. A plunger 6 operates in the vertical receiving end of the spout or conductor and may be operated in any suitable manner. As shown in the present instance the plunger stem 7 is 85 connected with a piston 8 working in a cylinder 9, connected by suitable conductors 10 and 11 with a valve 12. The valve 12 controls the supply and exhaust of air furnished from any suitable source of air 90 supply to and from the cylinder 9, by which the piston 8 is operated to project and retract the plunger. Instead of a pneumatically operated plunger, any other style of pneumatic feed, or pneumatic mechanical, 95 or manually actuated plunger feed mechanism may be employed.

I have not deemed it necessary to show other than certain types of feed mechanism, as the feed mechanism, broadly considered, 100 constitutes no part of the present invention.

The outer or discharge end of the spout or conductor 4 terminates in a mouth piece or nozzle 13 having a tapered chamber 14

communicating with a front discharge port or outlet 15 and a threaded bottom socket or outlet 16. The port or outlet 15 is controlled by a sliding, dove-tailed cut off plate 17 movable in a dove-tailed guide way 18 and provided with one or more discharge openings 19. This plate is adjustable to one position to cut off communication between the outlet 15 and the opening or openings 19, when the mouth piece is not in use or is employed for other than making front horizontal castings; and is adjustable to a certain position in which the opening or openings 19 register with the outlet 15 for the discharge of metal in making front horizontal castings. A set screw or other suitable device 20 may be employed to secure the plate 17 in its described positions.

The socket 16 is threaded to receive a bottom outlet controlling device consisting of two parts, to wit, a plug or closure member 21 and a valve or controlling member 22. The plug or closure member has its body externally threaded to engage the threads of the socket 16 and is provided at its base with an angular flange 23 for the application of a wrench or like tool, whereby it may be turned or adjusted, applied and removed. Formed in said plug or closure member is a tapered passage 24 adapted to receive the tapered valve or controlling member 22, which fits snugly therein, said member 21 being provided at diametrically opposite sides of the passage 24 with downwardly extending feed grooves 25. The member 22 is provided at its upper end with a flange 26 to rest upon the top of the member 21, and is formed with a cavity 27 opening through its top and communicating at its lower end with ports 28 adapted to register with the grooves 25. When the plug or closure member 21 is turned up to a fully applied position, the grooves 25 are disposed so that they are out of register with the ports 28, so that the bottom outlet of the mouth piece or nozzle will be closed against the discharge of metal, while when said mouth piece or nozzle is turned downward to a predetermined extent the grooves 25 will be brought in position to communicate with the ports 28, when the member 22 is turned to a certain position by means of the controlling valve, so that the molten metal may be discharged through the bottom outlet for under-head vertical casting.

The tapered controlling valve 29 fits within the valve chamber 14, and is adapted to be applied and removed through the bottom outlet. This valve is formed in its base with sockets 30 to receive pins or projections 31 on the member 22, whereby said member 22 will be coupled to the valve 29 for movement therewith. The valve is

formed with a horizontal transverse passage 32 adapted to connect the discharge duct in the spout 4 with the outlet 15, and is also provided with a vertical passage 33 leading downwardly from the passage 32 and communicating with the pocket 27 in the member 22, whereby the bottom outlet 70 is also adapted to be placed in communication with the duct in the spout 4. When the valve 29 is turned to a cut off position, in which the passage 32 is out of register with the spout and outlet 15 the flow of the molten metal to either the front outlet or the bottom outlet is prevented, but when the valve is turned to a position in which its passage 32 registers with the spout and outlet 15, the apparatus is in condition for either front horizontal or underhead vertical casting, the discharge of the metal in one direction or the other being controlled by the cut off plate 17 and the cut off or controlling member 21.

The upper end of the valve 29 is integral with a stem 34 and is provided with a cylindrical threaded portion 34' engaged by a split clamping nut 35 resting upon a hard metal friction disk or washer 35' seated upon the top of the mouth piece 13, whereby the valve is adjustably supported and may be maintained in close engagement with its seat. The upper end of the stem 34 is arranged in proximity to the stem 36 of the air valve 12, the proximate ends of said stems being connected by an operating lever 37 by which the two valves 12 and 29 may be simultaneously turned to feed and cut-off positions.

When the valve 29 is in the position shown in Fig. 1, and the cut off devices 17 and 21 are adjusted as shown in said view, the spout is closed against the discharge of the metal while the plunger 6 is in raised or retracted position. If it be desired to make a front horizontal casting, the plate 17 is adjusted to bring the discharge opening 19 into communication with the outlet passage 15, whereupon by turning the lever 37 in the proper direction the valves 12 and 29 will be simultaneously opened, the plunger 6 being forced downward and expelling a charge of metal from the spout and through the valve passage 32, outlet 15 and opening 19 into the die mold, which is suitably arranged in position to receive the expelled charge of metal. Upon then turning the lever 37 to its normal position, the flow of metal will be cut off and the plunger retracted. If it should be desired to make a vertical underhead casting, the cut off 17 is adjusted to closed position, and the closure member 21 unscrewed to a predetermined extent, so that when the lever 37 is again moved to open the valves 12 and 29, the

plunger 6 on its downward movement will discharge a charge of metal through the valve passages 32 and 33, the chamber 27, ports 28, grooves 25 and lower end of the chamber 24, into the properly supported die mold, it being understood that in the rotation of the valve 29 rotary movement will also be communicated to the under-feed valve member 22 to bring its ports 28 into register with the previously set grooves 25, whereby the under-feed controlling mechanism is adjusted for under-feed casting. By means of a mouth piece or nozzle of the construction described, and the simple adjustment of one or the other of two controlling members, it will thus be seen that the same apparatus may be employed for horizontal front casting or under-head vertical casting, without changing or varying the working parts employed. It will also be seen that at the same time the manipulation of the handle 27 will not only adjust the valve 29 but will simultaneously effect the operation of the feed plunger 6.

To render the apparatus capable of making over-head castings, I provide a transfer or conducting tube which is adapted for interchangeable use upon the mouth piece with the valve 29. This over-head conductor comprises a tube 38 provided at its lower end with a tapered body 39 having a basal flange 40 and a crown portion or sleeve 41. The tapered body 39 being provided with an L-shaped passage 42 to connect the bore of the tube 38 with the duct or passage of the spout 4. The sleeve 41 is adapted to be engaged by the split ring and clamp 35, whereby the transfer tube is clamped in position, the flange 40 bearing against the shoulder formed at the top of the socket 16 to close the base of the chamber 14 against any possibility of leakage of the metal. When the parts are thus arranged for over-head casting, the actuation of the plunger 6 will force the metal up through the tube 38 into the over-head mold 43.

In the use of the transfer tube for over-head casting, it is desirable to provide means to prevent the metal from being chilled on its flow to the tube. To this end I may provide a guard jacket or casing 44 to surround the mouth piece and tube, and which may be detachably secured to the front of the machine frame or casing by screws or other suitable fastenings 45. With this arrangement of the parts, a burner 46 may be disposed below the mouth piece and within the lower end of the jacket 44, and the flame of the burner may impinge against the plug or closure member 21. I may also employ with this arrangement a manually operable lever 47 for directly actuating the plunger stem 7, which lever may be suitably fulcrumed to

the frame of the machine, as at 48, and provided with a slot 49 to receive and engage a pin 50 suitably secured to the stem 7, by which the lever may be moved vertically in an arcuate path to transfer motion to the plunger stem. By thus simply substituting the over-head transfer tube for the controlling valve 29, over-head casting may be made when desired, and it will be evident that by the use of a mouth piece and interchangeable parts of the character disclosed a single machine may be employed for making various types of castings in a ready, quick and convenient manner.

I claim:—

1. In a die casting machine, a discharge spout, a mouth piece provided with a lateral opening and a bottom opening, controlling elements for both openings, and a valve in the mouth piece adjustable to control communication between the spout and either opening. 80

2. In a die casting machine, a discharge spout, a mouth piece communicating therewith and provided with discharge openings at the front and bottom thereof, controlling devices for said discharge openings, where- 90 by the same may be independently opened and closed, a valve in the mouth piece for connecting either of said discharge openings with the spout, and means for operating said valve. 95

3. In a die casting apparatus, a discharge spout, a mouth piece connected therewith and having a front discharge outlet and a bottom discharge outlet, a member for controlling the front discharge outlet, a rotary valve in the mouth piece for opening or closing communication between the spout and said outlets, a controlling member for the bottom outlet having a discharge port, and a valve member controlling said port 105 and adjustable with the valve in the mouth piece. 100

4. In a die casting machine, a discharge spout, a mouth piece connected therewith and provided with a front discharge outlet 110 and a bottom discharge outlet, a controlling device for the front discharge outlet, a rotary valve in the mouth piece controlling communication between the spout and both discharge outlets, an adjustable closure 115 member for the bottom discharge outlet, said closure member having a threaded engagement with the mouth piece and provided with a discharge passage and grooves communicating therewith, and a valve mem- 120 ber connected for rotation with the valve member in the mouth piece, said valve member being arranged to fit within the passage in said closure member and having outlets leading thereto, said outlets being adapted 125 for cooperation or not with said closure

member by predetermined adjustments of the latter.

5. In a die casting machine, the combination of a discharge spout, a mouth piece connected therewith and provided with front and bottom outlets, controlling members for said outlets, a valve for controlling communication between said spout and the respective outlets, and a conductor inter-

changeable with the valve for use upon the mouth piece, said conductor being provided with a discharge tube for over-head casting.

In testimony whereof I affix my signature in presence of two witnesses.

JAMES BATE.
